UNITED STATES PATENT OFFICE.

ARTHUR BATES, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

APPARATUS FOR ATTACHING UPPERS TO SOLES IN THE MANUFACTURE OF SHOES.

1,426,343.

Specification of Letters Patent. Patented Aug. 22, 1922.

Application filed October 25, 1917. Serial No. 198,406.

To all whom it may concern:

Be it known that I, ARTHUR BATES, a subject of the King of England, residing at Leicester, Leicestershire, England, have invented certain Improvements in Apparatus for Attaching Uppers to Soles in the Manufacture of Shoes, of which the following description, in connection with the accompanying drawings, is a specification, like reference characters on the drawings indicating like parts in the several figures.

This invention relates to an improved apparatus for attaching uppers to soles in the manufacture of shoes.

The invention has reference more particularly to the attachment of the upper to the sole by metallic fastenings inserted at intervals through the upper and into the sole. In the use of metallic fastening machines to attach uppers to soles, the shoe with a last therein is presented in operative relation to the fastening inserting mechanism with the upper in engagement with a part of the fastening inserting mechanism adjacent to the passage through which the fastenings are driven. It has been found in the operation of such machines that the upper is likely to be so stretched over the sole between the successive fastenings as to cause a gradual accumulation of material of the upper in advance of the inserted fastenings which must be disposed of in a large fold or pucker. There is a special tendency to the formation of these undesirable folds or puckers in the upper at the curved parts of the sole edge such as the toe.

An object of the invention is to provide mechanism for use in the attachment of an upper to its sole without the formation of undesirable folds or puckers in the material of the upper.

In this aspect, an important feature of the invention resides in the provision of a member constructed and arranged to engage the upper at a point adjacent to the passage of the throat piece of the fastening inserting mechanism and to retain the upper during relative movement of the upper and sole. As shown, the upper engaging member is so formed as to be received in a groove in the sole and to operate to press the upper thereinto.

In the illustrative construction there is also provided a support to sustain the shoe in operative relation to the throat piece, the support being constructed and positioned relatively to the throat piece to engage and support the opposite side of the sole from that in which the fastenings are being inserted at a point substantially in alignment with the throat piece and for fulcruming movement of the shoe while maintaining the shoe in operative relation to the throat piece.

The novel mechanism is herein shown as embodied in a staple fastening machine such as is disclosed in the patent to Borden, No. 1,016,930, granted February 13, 1912. The scope of the invention is not, however, to be limited thereby.

Other objects and features of the invention will appear as the description proceeds.

In the drawings,

Fig. 1 is a side elevation of part of a stapling machine of the type illustrated in the patent above cited having a throat piece and work support constructed in accordance with the present invention and illustrating a clog shoe presented to the machine in position to have its upper secured to its sole.

Fig. 2 is a plan view of the throat piece and the parts carried thereby, and

Fig. 3 is a view in front elevation, showing the work support and throat piece and a clog mounted on the work support in operative engagement with the throat piece.

The frame of the stapling machine is designated 2 and has mounted thereon a fixed bracket 4 seated in a socket 6 formed in a projecting portion of the frame and secured in said socket by a screw 8. The bracket 4 has its end outturned away from the machine at 10 and has pivoted thereto the bell crank member 12 by the fulcrum stud 14, the bell crank member 12 being secured on the stud by a set screw 16. The short end 18 of the bell crank lever is forked and has rotatably mounted in bearings formed in the forked portions thereof a rod 20 which receives rotatably a pin 22 having a reduced portion indicated at 24 permitting rotation of the pin 22 relatively to the rod 20 but preventing lengthwise movement of the pin relatively to the rod. The pin 22 is threaded at the end toward the

frame of the machine and the threaded portion of the pin is received into a cylinder 26 rotatably mounted in the upper end of the bracket 4. The other end of pin 22 is provided with a milled head 28.

The longer arm 30 of the bell crank member 12 is formed with a work supporting surface upon which is secured by screws 32, a sheet 34 of leather or other material of a nature adapted to prevent slipping of the edge of a sole supported thereon relatively thereto under the force exerted by the fastening inserting mechanism. The pin 22 is adapted to be manipulated by the operator to adjust the position of the work supporting arm of the bell crank lever, the upper surface of said work supporting arm as shown in the drawing being adjusted to an angle of about 30 degrees to the vertical.

20 I have described above and illustrated in the drawing a convenient construction of work support for the purposes of the invention. This support forms no part of the present invention but is disclosed and claimed in my 25 application Serial No. 432,304 renewed December 21, 1920 (originally filed October 4, 1917, Serial No. 194,721). It is to be understood that any other suitable construction of work support can be substituted therefor within the scope of the invention as defined in the appended claims. The work supporting attachment may even be entirely dispensed with and the machine used with the shoe supported only by the hands of the 30 operator.

The throat piece 36 is supported from the head of the machine by the arm 38 in the manner fully illustrated and described in the before-mentioned patent, the passage of 40 the throat piece which receives the fastening for attaching the upper to the sole being indicated at 40 and said throat piece having its lower end beveled on either side as indicated at 42 and 44. The throat piece is reduced in width at its delivery end and carries a bar 46 provided with grooves 48 in each end thereof in which are mounted plates 50 and 52 detachably secured to the bar by headed screws 54 and 56 respectively. 45 The plates 50 and 52 have their lower ends arranged in alignment with the passage 40 of the throat-piece and with each other and formed adjacent to the mouth of the throat piece 36 with teeth 58 and 60 respectively. 50 The plates 50 and 52 are adapted to dig into the upper of the clog, the teeth 58 of the plate 50 at the left of the throat piece being inclined somewhat to the right and the teeth 60 of the plate 52 at the right of the throat piece being inclined somewhat to the left, the teeth of both plates being inclined in a direction toward the mouth of the throat piece 36. It will be noted by reference to Fig. 3 of the drawings that the reduction in width of the throat- 55 piece 36 at its lower or delivery end permits

the inner edges of plates 50 and 52 partially to underlie the passage 40 at the lower ends, the inner edges of the plates 50 and 52 thereby forming extensions of the walls of the passage 40 and operating to guide the fastenings below said passage.

In lasting shoes by means of the above-described machine, the operator takes an upper with a last in it and already connected at a few points to the sole edge and thrusts 75 the work upwardly against the throat piece so that the teeth of the plate 50 or 52, depending upon which side of the shoe is being operated upon, will engage the upper near its margin and push the margin of the 80 upper into the groove of the sole. Assuming, as indicated in Fig. 3 of the drawing, that the left side of the shoe looking toward the toe is being operated upon, a fastening is first inserted through the upper at a point 85 near the center of the toe portion of the sole, preferably at a distance therefrom equal to one-half of the distance between successive fastenings. Following the insertion of the first fastening, indicated at A, in Fig. 3, the 90 sole and upper are again presented to the throat piece in a position such that the teeth 58 of the plate 50 will engage the margin of the upper and force the same down into the groove of the sole, the upper and sole being 95 engaged by the teeth 58 at a point such that the passage 40 of the throat piece aligns with a point on the sole somewhat further from the fastening previously inserted than the point at which the next succeeding fastening is to be inserted.

The sole is then moved to the left to bring the point on the sole at which the next succeeding fastening is to be inserted into alignment with the passage 40 of the throat piece 105 36, the points of the teeth 58 digging into the upper and holding it stationary during the movement of the sole. The fastening indicated at B in Fig. 3 of the drawings is then driven into place, the relative movement of the sole and upper previously to the insertion of the fastening having caused a little of the fullness of the upper to be taken up between the fastenings A and B. The fastening B having been inserted, the 110 sole and upper are again presented into operative relation to the throat piece, the teeth 58 of the plate 50 again engaging the upper in the groove of the sole. The point at which the next succeeding fastening is to be 115 inserted is indicated at C in Fig. 3 of the drawings and following the engagement of the upper by the teeth 58, the shoe is again moved to the left whereby the point C of the sole is moved into alignment with the 120 passage 40 of the throat piece and the upper being held against movement by the teeth 58, a little of the fullness thereof is passed back toward the fastening B. The third fastening is then inserted. By successively 125 130

repeating these operations the operator can succeed in reaching the side of the toe without finding that he has an excess of material to dispose of or has disposed of the material by one or more unsightly puckers or pleats.

The operator having completed the insertion of the fastenings on the left side of the shoe, turns the shoe backward, and presents 10 the toe of the shoe into operative relation with the throat piece at a point on the right side of the center of the toe. In the operation of inserting fastenings on the right side of the shoe the upper and sole will be 15 presented to the throat piece in a position such that the margin of the upper will be engaged by the teeth 60 of the plate 52. In starting the operation on the second side of the shoe the sole will be so positioned relatively to the passage 40 of the throat piece 20 that the passage 40 will be in alignment with a point on the sole more remote from the fastening A than the point at which the fastening is to be inserted. Following the engagement of the upper by the teeth 60 of 25 plate 52, the shoe will be moved to the right far enough to bring the point of the sole at which the fastening is to be inserted into alignment with the throat piece 40, thus 30 causing a little of the fullness of the material of the upper to be passed back toward the fastening A. By successive operations of the kind above described, the attachment of the upper to the sole on the right side of 35 the shoe is completed.

When the work supporting attachment previously described is used the operator rests the edge of the tread face of the sole on the opposite side of the sole from that in 40 which the fastenings are being inserted upon the covered flattened surface of the arm 30 of the bell crank member 12, which is previously adjusted to a convenient angle by rotation of the screw threaded pin 22, 45 using the arm 30 of the bell crank member as an abutment to resist the thrust of the driver of the machine and as a fulcrum in forcing the work against the throat piece and in turning the work relatively to the 50 throat piece.

When the work supporting attachment is used the shoe is not moved bodily following engagement of the upper with the throat piece, the point of the sole at which the fastening is to be inserted being brought into 55 alignment with the passage 40 of the throat piece by tipping movement of the sole on the supporting arm 30. The length of the flattened and covered portion of the arm 30 of the bell crank member 12 is such that no matter at what part of the contour of the sole the fastenings are being inserted, a part of the tread face edge of the opposite side of the sole may be rested upon the covered 60 portion of the arm to enable the thrust of 65

the driver to be taken up by said arm and to permit of the use of the arm as a fulcrum for the sole, in the manner described.

It will be understood that the surface 34 of the face of the part 30 which carries it, is 70 relatively narrow so as to give full freedom to the operator in imparting tipping movements to the work, and that the surface 34 is of a nature to maintain the edge of the sole against movement under the action of 75 the fastening inserting devices.

It will be further understood that working of the material into position for fastening may be accomplished without movement of the sole in the direction of the groove 80 formed therein, the sole being moved in a direction transversely of the groove, the teeth of the plate engaged by the member operating to engage the upper initially above the groove and to drag or push the upper 85 toward and into the groove.

The term "throat-piece" which appears in some of the claims is not intended to limit the claims but to refer to a part of any form having a passage which guides the fastenings to the work into which they are inserted. 90

The method practiced in the use of the apparatus of this invention is claimed in my application Serial No. 531,632 filed Jan. 95 25, 1922.

Having fully described my invention, what I claim as new and desire to secure by Letters Patent of the United States is:—

1. A machine of the class described comprising, in combination, mechanism for inserting fastenings through an upper into its sole constructed and arranged for engagement with the upper, a work supporting abutment spaced therefrom and constructed 100 and positioned relatively to the fastening inserting mechanism for engagement with the corner of the sole formed by the junction of the edge face of the sole and the tread face opposite to the point at which fastenings are 105 being inserted and in substantially vertical alignment with the portion of the fastening inserting mechanism which engages the upper, said abutment being further constructed and arranged for fulcruming the 110 sole for movement of the sole relatively to the upper at the point where the upper engages the fastening inserting mechanism.

2. A machine of the class described comprising, in combination, fastening inserting 115 mechanism embodying a member having a toothed portion constructed and arranged relatively to the fastening inserting mechanism to engage the margin of the upper of a shoe presented in operative relation to the 120 fastening inserting mechanism, means for supporting the shoe in operative relation to the fastening inserting mechanism constructed and positioned to engage the 125 opposite side of the shoe from that in which 130

fastenings are being inserted at a point substantially in alignment with the fastening inserting mechanism for fulcruming the shoe for movement of the shoe relatively to the 5 fastening inserting mechanism while supported on said supporting means in operative relation to the fastening inserting mechanism to take up a part of the fullness of the upper between any two successively inserted 10 fastenings, said supporting means being further constructed and arranged to permit the shoe to be readily moved therefrom in order that bodily movement of the shoe may be effected to present a different portion of the 15 upper and sole into operative relation to the fastening inserting mechanism.

3. In a machine of the class described, fastening inserting mechanism comprising a throat piece having a beveled end and having 20 a passage formed therein to receive fastenings to attach the upper to the sole and being operable to push the upper into the groove of the sole, means for supporting the work constructed and positioned for engagement 25 with the opposite side of the sole from that in which the fastenings are being inserted at a point substantially in alignment with the passage of the throat piece and constructed and arranged to permit fulcruming 30 movement of the shoe after engagement of the throat piece with the upper and groove of the sole to move the sole relatively to the part of the upper engaged by the throat piece.

4. A machine of the class described comprising, in combination, mechanism for inserting fastenings through an upper into its sole constructed and arranged for engagement with the upper, a work supporting abutment spaced therefrom and constructed 40 and positioned relatively to the fastening inserting mechanism for engagement with the corner of the sole formed by the junction of the edge face of the sole opposite to the point of fastening insertion and the tread face of 45 the sole at a point substantially in vertical alignment with the portion of the fastening inserting mechanism which engages the upper, said abutment being further constructed and arranged to permit fulcruming 50 the sole for movement of the sole relatively to the upper at the point where the upper engages the fastening inserting mechanism, the work supporting surface of the abutment being covered with a strip of material such 55 as will prevent slipping of the sole on the abutment under the force exerted by the fastening inserting mechanism.

5. A machine of the class described comprising, in combination, mechanism for inserting fastenings through an upper into its sole constructed and arranged for engagement with the upper, a work supporting abutment spaced therefrom and constructed 60 and positioned relatively to the fastening 65 inserting mechanism for engagement with

the corner of the sole formed by the junction of the edge face of the sole opposite to the side of the sole in which fastenings are being inserted and the tread face of the sole at a point substantially in vertical alignment with the portion of the fastening inserting mechanism which engages the upper, said abutment being further constructed and arranged to permit fulcruming the sole for movement of the sole relatively to the upper at the point where the upper engages the fastening inserting mechanism, and means for adjusting said abutment angularly to adapt it to soles of different sizes. 70 75 80

6. In a machine of the class described, in combination, a throat-piece having a passage formed therein to receive fastenings for attaching an upper to its sole, a member projecting beyond the delivery end of 85 the throat-piece to engage the upper when the shoe is in operative relation to the throat-piece, and a support to sustain the shoe in operative relation to the throat-piece and constructed and positioned relatively to the member and throat-piece for fulcruming the shoe for movement of the shoe upon the edge opposite to the throat-piece when in operative relation to the throat-piece while maintaining the upper in engagement with 90 95 said member.

7. In a machine of the class described, in combination, a throat-piece having a passage formed therein to receive fastenings for attaching an upper to its sole, a support to sustain the shoe in operative relation to the throat-piece and constructed and positioned relatively to the throat-piece for fulcruming the shoe for movements of the shoe while in operative relation to the 100 throat-piece, a fixed member constructed and arranged to engage the upper during fulcruming movements of the shoe when operating on one side of the shoe and a second fixed member constructed and arranged to 105 engage the upper during fulcruming movements of the shoe when operating on the other side of the shoe.

8. In a machine of the class described, in combination, a throat-piece having a passage formed therein to receive fastenings for attaching an upper to its sole, a support to sustain the shoe in operative relation to the throat piece constructed and positioned relatively to the throat-piece for 110 fulcruming the shoe for movement of the shoe while in operative relation to the throat-piece, and means carried by the throat-piece to retain the upper against movement during fulcruming movement of 115 the shoe on the support.

9. In a machine of the class described, in combination, a throat piece having a passage formed therein to receive fastenings for attaching an upper to its sole, said 120 125 130

throat-piece being constructed and arranged to permit movement of the shoe while in operative relation thereto, and means carried by the throat-piece to retain the upper 5 against movement during movement of the shoe to cause the upper to be fulled between the tack last driven and the said means.

10. In a machine of the class described, in combination, a throat-piece having a passage formed therein to receive fastenings for attaching an upper to its sole, a support to sustain the shoe in operative relation to the throat-piece constructed and positioned relatively to the throat-piece for 15 fulcruming the shoe for movement of the shoe about its sole edge while in operative relation to the throat-piece, and an upper engaging member adjacent to the throat-piece operating to retain the upper against 20 movement during fulcruming movement of the shoe.

11. A machine of the class described comprising, in combination, mechanism for inserting fastenings through an upper into its sole constructed and arranged for engagement with the upper, and a work supporting abutment spaced therefrom constructed and positioned relatively to the fastening inserting mechanism for engagement with 25 the corner of the sole formed by the junction of the edge face of the sole opposite to the side of the sole in which fastenings are being inserted and the tread face of the sole at a point substantially in vertical 30 alignment with the portion of the fastening inserting mechanism which engages the upper.

12. A machine of the class described comprising, in combination, mechanism for inserting fastenings through an upper into its sole constructed and arranged for engagement with the upper, and a work supporting abutment spaced therefrom and constructed and positioned relatively to the 40 fastening inserting mechanism for engagement with the corner of the sole formed by the junction of the edge face of the sole opposite to the side of the sole in which fastenings are being inserted and the tread 45 face of the sole at a point substantially in vertical alignment with the portion of the fastening inserting mechanism which engages the upper, the work supporting surface of the abutment being covered with a strip of 50 material such as to prevent slipping of the sole on the abutment under the force exerted by the fastening inserting mechanism.

13. A machine of the class described comprising, in combination, mechanism for inserting fastenings through an upper into its sole constructed and arranged for engagement with the upper, a work supporting abutment spaced therefrom constructed and positioned relatively to the fastening 60 inserting mechanism for engagement with 65

the corner of the sole formed by the junction of the edge face of the sole opposite to the side of the sole in which the fastenings are being inserted and the tread face of the sole at a point substantially in vertical alignment with the portion of the fastening inserting mechanism which engages the upper, and means for adjusting said abutment angularly.

14. In a machine of the class described, in combination, a throat-piece having a passage formed therein to receive fastenings to attach an upper to its sole, and a member connected to the throat-piece having a work-engaging portion extending laterally at each 75 side of the throat-piece and downwardly beyond the end of the throat-piece and substantially in the plane of the passage formed in the throat-piece.

15. In a machine of the class described, in combination, a throat-piece having a passage formed therein to receive fastenings to attach an upper to its sole, a member connected to the throat-piece at one side thereof having a toothed upper engaging portion extending beyond the end of the throat-piece and substantially in the plane of the passage formed therein, and a work support for sustaining the work against said toothed upper engaging portion and constructed and arranged to permit a fulcruming movement of the shoe thereon to be effected to take up part of the fullness of the upper.

16. In a machine of the class described, in combination, a throat-piece having a passage formed therein to receive fastenings to attach an upper to its sole, and plates connected to the throat-piece on opposite sides thereof each having a toothed engaging portion extending beyond the end of the throat-piece, said engaging portions being substantially in alignment with the end of the passage formed in the throat-piece and with each other and said plates being disposed substantially in the plane of the passage formed in the throat-piece.

17. In a machine of the class described, in combination, a throat-piece having a passage formed therein to receive fastenings to attach an upper to its sole, plates connected to the throat-piece on opposite sides thereof having their end portions extending beyond the end of the throat-piece and arranged in substantial alignment with the end of the 115 passage formed in the throat-piece and with each other, said portions being formed with teeth inclined toward each other and toward the passage of the throat-piece.

18. In a machine of the class described, in combination, a throat-piece having a passage formed therein to receive fastenings to attach an upper to its sole, and a member connected thereto wholly at one side thereof having its end portion extending beyond 125 130

the end of said throat-piece and being formed with teeth inclined toward the mouth of the throat-piece to assist in gathering the upper on one side of the throat-piece toward the throat-piece.

19. In a machine of the class described, a throat-piece having a passage formed therein to receive fastenings to attach an upper to its sole, and plates connected to the throat-piece having their end portions extended beyond the mouth of the throat-piece, said end portions being formed with teeth extending toward each other and toward the mouth of the throat piece.

20. In a machine of the class described, in combination, a throat-piece having a passage formed therein to receive fastenings to attach an upper to its sole, and members detachably connected on opposite sides of the throat-piece having their ends extended beyond the end of the throat-piece and in substantial alignment with the end of the passage formed in the throat-piece and with each other.

21. In a machine of the class described, in combination, a throat-piece formed with a reduced portion at the delivery end thereof, and having a passage formed therein to receive fastenings to attach an upper to its sole, and a member connected to the throat-piece having a work-engaging portion extending beyond the end of the throat-piece, substantially in alignment with the delivery end of the passage in the throat-piece and located closely adjacent to the end of the passage in the reduced portion of the throat-piece.

22. In a machine of the class described, in combination, a throat-piece having a pas-

sage to receive fastenings to attach an upper to its sole, and formed with a reduced portion at its delivery end surrounding the mouth of the passage, members connected to the throat-piece on opposite sides thereof having work engaging end portions extending beyond the end of the throat-piece, said members and the reduced portion of the throat-piece being constructed and arranged to cause the edges of said members adjacent to the passage of the throat-piece to guide the fastenings beyond the delivery end of the throat-piece.

23. In a machine of the class described, in combination, a throat-piece having a passage formed therein to receive fastenings to attach an upper to its sole, and a member connected to the throat-piece having a work-engaging portion extending beyond the end of the throat-piece, the edge of said member adjacent to the throat-piece forming an extension of the wall of said passage beyond the end of the throat-piece.

24. In a machine of the class described, in combination, a throat-piece having a passage formed therein to receive fastenings to attach an upper to its sole, and members connected to the throat-piece on opposite sides thereof having work-engaging portions extending beyond the end of the throat-piece, the edges of said members adjacent to the throat-piece forming extensions of the walls of the passage of the throat-piece beyond the end of the throat-piece.

In testimony whereof I have signed my name to this specification.

ARTHUR BATES.
